SQUEEGEE OPERATING AND CONTROL
MECHANISM

Stanley L. Frank, Oakland, Calif.

Application September 25, 1948, Serial No. 51,283

10 Claims. (Cl. 101—123)

1

My invention relates to screen printing apparatus and more particularly to squeegee operating and control mechanism for such apparatus.

Among the objects of my invention are:

(1) To provide a novel and improved squeegee operating and control mechanism for screen printing apparatus;

(2) To provide a novel and improved squeegee operating and control mechanism for screen printing apparatus, in which the squeegee shall automatically reverse at the termination of each stroke;

(3) To provide a novel and improved squeegee operating and control mechanism for screen printing apparatus which will assure substantially uniform continuous pressure of the squeegee against the screen throughout the effective stroke of the squeegee;

(4) To provide a novel and improved squeegee operating and control mechanism for screen printing apparatus, which shall assure both ends of the squeegee traveling in synchronism at all times throughout each stroke;

(5) To provide a novel and improved squeegee operating and control mechanism for screen printing apparatus, in which the squeegee terminates its stroke in a reversal of position, ready for the start of its return stroke.

Additional objects of my invention will be brought out in the following description of a preferred embodiment of the same, taken in conjunction with the accompanying drawings wherein—

Figure 1 is an elevational view in section, taken longitudinally through the screen printing apparatus with my novel and improved squeegee operating and control mechanism installed;

Figure 2 is a fragmentary plan view of the apparatus of Figure 1;

Figure 3 is an elevational view in section, transversely of the apparatus of Figure 1 and taken in the plane 3—3 of Figure 1;

Figure 4 is a three-dimensional view of one end of the squeegee operating and control mechanism of the present invention;

Figure 5 is a view in section through the squeegee operating and control mechanism of Figure 4, showing one end thereof in elevation.

Referring to the drawings for details of the preferred embodiment of the present invention, the same is shown installed in conventional screen printing apparatus involving a platen 1 supported on a frame 3 to which is hingedly secured a rectangular frame 5 on which is stretched a silk screen 7 enabling the screen to be raised

2

and lowered with respect to the surface of the platen.

Ink or paint 9 employed in printing is placed on the upper surface of the screen and spread over the surface thereof by means of a squeegee 11 which is run over the surface of the screen in the process of printing.

A sheet 13 of blank paper, placed upon the platen beneath the silk screen, will receive such paint as penetrates through the pores of the screen during such movement of the squeegee. By placing a stencil 15 intermediate the screen and such paper, the stenciled information will be reproduced on the paper. The paint in the meantime causes the stencil to effectively adhere to the undersurface of the screen, whereby, upon lifting the screen following a stroke of the squeegee, the paper with its printed information thereon may be freely removed from the platen and a fresh sheet of paper substituted.

The present invention resides specifically in the mechanism for operating and controlling the squeegee, which, in the present invention, is adapted to function on both its forward and return strokes, and is designed to push the ink or paint ahead of it, as I have found this to produce more uniform results, in that the tendency for a squeegee to ride over the ink supply is thereby minimized.

Such operating and control mechanism involves means mounted on and extending along each longitudinal side of the screen frame for movably supporting a squeegee carrier assembly. Such supporting means includes a track 17 and associated rack 19 running along the longitudinal side of the screen frame, and a guide rail 21 running along the inner side of the upper edge of a side wall 23, to fixedly support such guide rail in parallel relationship to the track and associated rack.

The squeegee carrier assembly involves a pair of carriers 25, one for each end of the squeegee 11 which is adapted to span the width of the printing screen. Each such end carrier includes a pair of assemblies, one, 27, which slidably engages the track for slidable movement therealong, while the other assembly 29 is resistively supported by the track-engaging assembly and slidably engages the guide rail 21.

With respect to details of construction, the track-engaging assembly involves a block 31 having a longitudinal groove in its undersurface permitting the block to straddle the rack and rest upon the track. The corresponding blocks of each carrier are interconnected by an angle iron

cross-piece 35 spanning the screen frame. Pivotally secured to the corner of each of the aforementioned blocks, on the inner surface thereof by a bolt 36, is a squeegee mount 37 for carrying one end of the squeegee.

The squeegee 11 may be of any conventional structure, but the one illustrated involves a bar 39 having an edge slot for receiving a rubber strip or scraper 41. The squeegee bar at each end is provided with a mounting pin 43 for insertion in a perforation provided in a squeegee mount for the purpose. Upon raising the squeegee mounts about their pivot axes, it will be apparent that the squeegee will be lifted from its operative position on the screen.

The resistively supported assembly 29 comprising the upper portion of a carrier, comprises a strip 45 having end brackets 47 and 49 adapted to slidably engage the guide rail and thus support the strip for slidable movement adjacent the inner edge of the guide rail. This strip is formed with a longitudinal slot 51 extending practically the full length thereof to receive a bolt or machine screw 53 extending downwardly through the slot and threadedly engaging the bearing block below, such bolt limiting the permissible movement of the strip with respect to the bearing block.

The slotted strip carries along its upper surface adjacent its inner edge, a lift-and-reversing cam 55. This cam is in the form of a flat segment standing on edge, the cam surface being formed by the upper edge of the segment sloping upwardly toward a peak from each end.

Such cam surface is adapted to be engaged by a cam follower or roller 57 which in the operating position of the squeegee, will occupy a position at one end of the cam.

As thus far described, if the upper or cam assembly 29 were held against movement along the guide rail, and pressure were brought to bear against the bearing block to produce relative movement between the track engaging assembly and the cam assembly, the squeegee mount at each end of the squeegee will be lifted about its pivot axis as the cam follower on the squeegee mount is forced to ride up the adjacent cam surface toward the peak of the cam; and as the squeegee mounts are thus lifted, the squeegee itself will be tilted upward to a vertical plane and raised above the screen to the position depicted in Figure 5. Continued relative movement between the two assemblies will cause the cam follower to descend on the other slope of the cam to gradually drop the squeegee back into contact with the screen and reverse its position.

Such reversing action of the squeegee is only desired however, at the termination of each stroke, and accordingly to secure such action at the proper time, I provide a stop pin 59 on the guide rail at a point approaching the end of each stroke, so that as the cam assembly strikes or abuts such a stop pin, to halt further movement thereof in the direction in which it was traveling, sufficient additional movement of the bearing block will be permitted to effect the desired reversal of position of the squeegee.

It is noted that the cam is not symmetrical in the embodiment of the invention illustrated, and this is attributable to the fact that in the reversed position of the squeegee, it will not necessarily occupy the same position relative to the pivot axis of the squeegee mount as previously, and accordingly, the cam surface is designed to compensate for this condition.

The reciprocating movement of the squeegee is imparted thereto by a rod 61 hingedly secured to the angle iron cross member 35 at the mid-point thereof, such rod constituting either a piston rod or a lever in a power application system.

The squeegee of the present invention is so mounted as to push the ink or paint ahead of it, as distinguished from the conventional method of dragging the ink along with it. A more positive and effective spreading of the coloring material over the screen is thereby assured.

Means are provided for equalizing the movement of the aforementioned end carriers 25 with respect to each other, to assure that one end of the squeegee shall not travel ahead of the other during any portion of its stroke, or, in other words, to maintain the squeegee at all times normal to its direction of movement.

Such means includes an equalizer shaft 63 journaled at each end in one of the bearing blocks. Each such bearing block is formed to provide a chamber for housing a pinion 65 mounted on such equalizer shaft adjacent the associated journaled end and in engagement with the rack. With such equalizer means installed and functioning, one end carrier assembly cannot move ahead of the other during any portion of the stroke of the squeegee, and consequently the squeegee itself will necessarily remain normal to its direction of movement at all times.

During the operating or functioning portion of the squeegee stroke, the squeegee is maintained in proper pressure contact with the screen by providing at each end of the squeegee, suitable means for positively holding the squeegee in the desired pressure contact with the surface of such screen.

Such means includes a pressure rail 67 affixed against the inner edge of the track, and extending substantially, though not quite, the whole distance between stop pins. Affixed to each end of the squeegee bar for cooperation with such rail, is a pressure roller 68 adapted to engage this rail and slide under it at the start of each stroke, the rail being cammed at each end to facilitate such engagement. In this manner, the squeegee will be positively held in its down or operating position at a desired pressure, until such roller rides from under such rail at the other end thereof, which is time to occur just prior to contact of the upper or cam assembly with a stop pin.

As the squeegee is thus depressed into pressure engagement with the screen, the angular rotation of the squeegee about its mounting pins is in a direction tending to reverse the squeegee. To avoid probable reversals of the squeegee under such circumstances, I have found it desirable that the squeegee be temporarily locked in the position it assumes at the end of each stroke so as not to be disturbed when the pressure rollers subsequently engage the pressure rails on the succeeding stroke.

With this in mind, the mounting bracket 47 of the cam assembly is formed with a notch 69 facing the associated squeegee mount 37, which mount is formed with an overhang 71 adapted to enter the notch at the termination of the return stroke, whereby the mount becomes locked against movement on its pivot axis. During what may arbitrarily be considered the forward stroke, it is contemplated that such locking engagement will be maintained until the cam assembly strikes the stop pin at the end of such forward stroke, when the squeegee mount will then be forced out of such locking engagement, permitting the cam fol-

lower associated therewith, to engage and ride over the cam in the process of reversing the squeegee, it being noted that by this time the squeegee pressure roller will have moved out of engagement with the pressure rail and so will not interfere with such reversal of the squeegee.

Following reversal of the squeegee at the far end of the forward stroke, a similar locking of the squeegee occurs in preparation for the return stroke. At this point it is accomplished by providing a shoulder 73 on the squeegee mount, which is adapted to slide in under the bracket 49 to thereby lock the mount against movement about its pivot axis.

From the above description of my invention in its preferred form, it will be apparent that the same fulfills all the objects recited therefor and while I have disclosed my invention in its preferred form and in considerable detail, the same is subject to alteration and modification without departing from the underlying principles thereof. I, accordingly, do not desire to be limited in my protection to such details, except as may be necessitated by the appended claims.
